United States Patent

Des. 241,818
Patented Oct. 12, 1976

241,818

COMPARTMENTED BOX

Frances V. Hejna, 44 State Highway,
Edgewater, N.J. 07020

Filed Dec. 23, 1974, Ser. No. 535,639

Term of patent 14 years

Int. Cl. D9—03

U.S. Cl. D9—185

FIG. 1

FIG. 2

FIG. 3

FIG. 4

FIG. 5

FIG. 1 is a perspective view of a compartmented box showing my new design with the cover separated from the box;

FIG. 2 is a top plan view on a reduced scale of the box with the cover removed;

FIG. 3 is a perspective view on a reduced scale with the cover in place;

FIG. 4 is a side elevational view thereof; and

FIG. 5 is a perspective view showing the underside of the cover.

I claim:

The ornamental design for a compartmented box, as shown.
